C. DAVIS.

CONTOUR BASE FOR PROJECTILES.
APPLICATION FILED SEPT. 30, 1913.

1,141,042.

Patented May 25, 1915.

Fig. 1.

1

A perspective view of a boat hull. The hull is elongated and tapers to a point at the stern. The upper deck is marked with diagonal hatching. Several parts are labeled with numbers: '4' is at the bow; '5' and '6' are at the stern; '7' is a vertical post on the left; '8' is a vertical post on the right; '9' is a small vertical post near the center; '10' is a rectangular opening in the deck; '12' is a vertical post on the left side; '14' is a vertical post on the right side; '15' is a vertical post near the stern; and '17' is a vertical post on the far left. The hull is shown with a thin line along its bottom edge.

CLELAND DAVIS, OF THE UNITED STATES NAVY, ASSIGNOR TO ORDNANCE DEVELOPMENT COMPANY, OF NEW YORK, N. Y., A CORPORATION OF DELAWARE.

CONTOUR-BASE FOR PROJECTILES.

1,141,042.

Specification of Letters Patent. Patented May 25, 1915.

Application filed September 30, 1913. Serial No. 792,680.

To all whom it may concern:

Be it known that I, CLELAND DAVIS, commander, United States Navy, a citizen of the United States, residing at Washington, in 5 the District of Columbia, have invented certain new and useful Improvements in Contour-Bases for Projectiles; and I do hereby declare the following to be a full, clear, and exact description of the invention, such as 10 will enable others skilled in the art to which it appertains to make and use the same.

The object of my present invention is to provide means for decreasing the resistance of the air to the flight of a projectile moving at high velocity. The universal form 15 of projectile consists of a cylindrical body with a tapering ogival, or head, and a flat base; by changing the contour or form of the point of the projectile, its flight through 20 the air has been greatly facilitated, but no practical means have yet been devised to apply the contour to the base of the projectile to reduce the backward pull during its flight 25 through the air. As is well known, this backward pull amounts to a considerable portion of the loss of energy, or velocity, for a given distance. This is due to the vacuum, or partial vacuum, which is created by the 30 displacement of the molecules of air by the passages of the shell itself, which, on account of the velocity of the shell, have not time to close in on the base and equalize the pressure. In other words, the object is 35 to provide such a form for the base of the projectile as will give a minimum resistance to reduce its retardation in air, in a manner similar to providing gradually tapering lines and curves for the hull of the ship, to minimize the resistance of its passage 40 through the water.

With a projectile, the problem is somewhat complicated, owing to other qualities which it is necessary for the projectile to possess, as, for example, the quality of perforating armor plate, and also the ability 45 to carry a large bursting charge. The shape of the projectile is also important when the capacity of the powder chamber is considered, and a flat base projectile, such as is 50 now universally used, enables a maximum charge to be used in the powder chamber, with due regard to the weight and shape.

In order to overcome the objections of increased weight, reduction of capacity of

bursting charge and reduction of the size of 55 powder charge, and at the same time give the proper form of base, I provide a hollow attachment tapering with a curve to give a minimum resistance. This attachment may be screwed on in the case of fixed ammunition, or slipped on and locked in place in 60 the case of larger calibers, in the manner shown, or in any other convenient way.

The attachment is filled with powder and this forms part of the propelling charge 65 itself, and is provided with an aperture on the rear end, which permits of the equalization of the pressure of the gases inside and outside the hollow contour. As the projectile travels down the bore, powder contained in the hollow contour evolves its 70 gases, and thus plays its part in giving the projectile its normal velocity at the muzzle.

I do not limit myself to the exact form or shape of contour base, as this can only be 75 determined by long experiment. But even a slight elongation of the base will have an appreciable effect in reducing the negative acceleration of the projectile. For larger caliber guns, the contour may be included 80 in the first section of the powder charge, so that the projectile may be first loaded into the gun in the usual way. The first section of the powder charge containing the contour is then loaded and shoved up against 85 the base of the projectile, slipping over the latter and being locked in place.

Reference is had to the accompanying drawings in which the same parts are indicated by similar reference symbols throughout the several views.

Figure 1 shows a fixed ammunition constructed according to my invention; Fig. 2 shows a section through part of the bore and powder chamber of the gun, with the 95 projectile and first section of the powder charge in elevation, and showing the invention as applied for use with guns of heavy caliber; and Fig. 3 is a detail showing in section a part of the projectile and the first section of the propelling charge 100 detached therefrom, and including the contour base.

Referring first to Fig. 1, 1 represents the projectile, 2 the contour base screwed on the 105 projectile, and 3 the cartridge case constructed of the usual or any desired form, and containing the propelling charge 4, part

of which propelling charge is also contained in the interior of the contour base 2, as shown.

In the form of device shown in Figs. 2 5 and 3, 5 represents part of the gun body having the bore 6 and powder chamber 7 of the usual or desired form. 8 represents the projectile, which is cut away at its rear end, as at O. To fit into the large end of the 10 contour base, the reduced portion of the shell is provided with sockets 9 to hold the tapered blocks 10 and the springs 11, which tapered blocks slip under the wedge faces 13 in the large end of the contour base, and 15 spring out under the action of the springs 11 into the sockets 14 in the contour base 12. While the springs 11 normally tend to hold the locking blocks 10 in engagement, the revolution of the shell will create such 20 centrifugal force as will tend to hold the same in the outer or locking position after the parts are assembled. The contour base 12 is preferably provided with a suitable disk 15, of celluloid, or other combustible material, tending to keep its larger end always 25 open and ready to assemble with the shell; and the body of the contour base is filled with powder 18, and is mounted in any suitable container 16, preferably the usual silk, 30 or flannel bag bound around with tapes 17, but any suitable container may be used. Thus, the contour base and the container with the powder included in both forms the first section of the propelling charge, 35 and the combustible head 15 serves to keep the larger end of the contour base open so that it may be conveniently connected to the projectile after the latter has been shoved home. The other sections of the powder 40 charge are inserted in the usual way.

While I have shown spring-operated locking blocks connecting the shell and the contour base together, any other suitable means connecting these two members may be adopted, if desired; and I do not mean to limit my invention to any particular means for accomplishing this purpose.

It will be obvious that various changes might be made in the herein described apparatus, and in the constructions, combinations and arrangements of parts without departing from the spirit of my invention.

Having thus described my invention, what I claim and desire to secure by Letters Patent of the United States is:—

1. The combination with a projectile of standard design and the propelling charge thereof of a hollow metal contour base secured to the rear end thereof and forming 60 with the outer shell of the projectile a continuous substantially ogival curve, the hollow contour base having a length of one-half or more of the length of the projectile

to which it is secured, and being provided with an enlarged opening in its rear, said contour base projecting into the propelling charge and containing a portion thereof, substantially as described. 65

2. The combination with a projectile of standard design and the propelling charge 70 thereof of a hollow metal contour base secured to the rear end thereof and forming with the outer shell of the projectile a continuous substantially ogival curve, the hollow contour base having a length of one-half or more of the length of the projectile to which it is secured, and being provided with an enlarged opening in its rear, said contour base projecting into the propelling charge and containing a portion thereof, with 75 means for detachably connecting said contour base to the rear of the projectile, substantially as described. 80

3. The combination with a projectile of standard design and the propelling charge 85 thereof of a holder for a section of the propelling charge, a hollow metal contour base mounted in said holder and adapted to slip over the rear end of the projectile, the said contour base when secured to the rear end of 90 the projectile forming with the outer shell of the projectile a continuous substantially ogival curve, the said hollow contour base being provided with an enlarged opening in its rear end, and the propelling charge being mounted in said holder and partly in said hollow contour base, with means for detachably connecting said contour base and with 95 it said holder to the base of the projectile, substantially as described. 100

4. The combination with a projectile of standard design of a holder for a section of the propelling charge, a hollow metal contour base mounted in said holder and adapted to slip over the rear end of the projectile, the said contour base when secured to the rear end of the projectile forming with the outer shell of the projectile a continuous substantially ogival curve, the said hollow contour base being provided with an enlarged opening in its rear end, and the propelling charge being mounted in said holder and partly in said hollow contour base, with means for detachably connecting said contour base and with it said holder to the base 110 of the projectile, said means comprising spring-impressed tapered blocks engaging in sockets in the contour base, substantially as described. 115

In testimony whereof, I affix my signature, in presence of two witnesses.

CLELAND DAVIS.
